UNITED STATES PATENT OFFICE.

THOMAS L. FRATES, OF LIVERMORE, CALIFORNIA.

INTERNAL-COMBUSTION ENGINE.

1,109,982.

Specification of Letters Patent.

Patented Sept. 8, 1914.

Application filed March 11, 1913. Serial No. 753,577.

To all whom it may concern:

Be it known that I, THOMAS L. FRATES, a citizen of the United States, residing at Livermore, in the county of Alameda, State of California, have invented certain new and useful Improvements in Internal-Combustion Engines; and I do hereby declare the following to be a full, clear, and exact description of the invention, such as will enable others skilled in the art to which it appertains to make and use the same.

This invention relates to internal combustion engines and has for an object to provide a novel inlet valve mechanism which will promote the quick distribution of fuel to all parts of the cylinder above the piston so that the most effective operation of the engine will be promoted.

Another object is to provide a novel exhaust valve mechanism which will require minimum attention for promoting its most effective operation.

With the above objects in view the invention consists of certain novel details of construction and combination of parts hereinafter fully described and claimed, it being understood that various modifications may be made in the minor details of construction within the scope of the appended claims.

In the accompanying drawings illustrating this invention:—Figure 1 is an elevation with portions broken away. Fig. 2 is a longitudinal sectional view. Figs. 3, 4, 5 and 6 are diagrammatic views showing the power, exhaust, suction, and compression strokes respectively. Fig. 7 is an enlarged longitudinal sectional view through one of the exhaust valve casings. Fig. 8 is a detail sectional view of a portion of one of the exhaust valve stems.

Referring now to the drawings in which like characters of reference designate similar parts, a two-cylinder internal combustion engine of the four cycle type is shown, the same including a crank case 10, cylinders 11, and pistons 12 working in the cylinders and connected by connecting rods 13 to respective cranks on a crank shaft 14. The cylinders are surrounded by a water jacket 15 having inlet and outlet connections 16 and 17 and also having a drain cock 18.

Between the heads 19 of the cylinders and the bottom 20 of the water jacket there is provided a flat fresh gas space 21 which is connected by suitable pipe connections 22 with a carburetor 23. In each cylinder head

and on opposite sides of the center thereof is formed a pair of valve seats 24 and 25 in which are seated valves 26 and 27 which control the passage of fresh gas from the space 21 into the cylinders. Of the pair of valves in each cylinder, one valve 26 opens downwardly and the other valve 27 opens upwardly, both valves moving simultaneously. The value of this feature is that fresh gas is admitted simultaneously from two points of considerable area on opposite sides of the center of the cylinder head and thus the quick intake of gas and quick distribution of the same throughout all portions of the cylinder above the piston is promoted and the most effective operation of the engine assured.

For actuating the inlet valves 24 and 25 of each cylinder a lever 28 is pivoted on a fulcrum 29 that is centered on the cylinder head, this lever being connected at one end to a rod 30 that projects into the crank case and is there equipped with a roller 31 which rides upon a cam 32 carried by a cam shaft 33, the latter being actuated by a suitable train of gearing 34 from the crank shaft 14, and so timed as to lift the rod 30 at the beginning of each intake stroke of the piston 12. The stem 35 of the valve 24 projects slidably through a suitable bushing 36 in the water jacket and terminally contacts with the free end of the lever 28, and the stem 37 of the valve 27 is loosely connected to the lever 28 on the opposite side of the pivot thereof from the valve stem 35. A helical spring 38 is confined under tension between a washer 39 on the valve stem 35 and the foot 40 of the fulcrum, and normally holds the valve 26 closed and the lever horizontal whereby the valve 27 is also held closed. When the lever is rocked by the cam, the valve 27 is opened upwardly and the valve 26 is opened downwardly with a resultant admission of fresh gas into the cylinder. When the cam releases the lever the spring 38 immediately returns the valves to closed position.

On each cylinder near the head thereof is arranged a substantially oblong valve casing 41 which communicates with the compression space 42 of the cylinder through a port 43. A slide valve 44 is confined in this casing and controls the exhaust of burnt gases from the cylinder. The valve is provided with a stem 45 which slidably projects through a bearing 46 on the cylinder

and terminally bears against a stem 47 that is extended into the crank case and is there equipped with a roller 48 which rides upon a quick acting cam 49 carried by a cam shaft 50 which is actuated by a train of gearing 51 driven by the crank shaft 14.

A helical spring 52 is confined under tension between the above mentioned bearings 46 and a collar 53 on the valve stem, this 10 spring causing the valve stem to abut and follow the cam actuated stem 47. The cam 49 is so constructed and timed as to quickly open the slide valve at the beginning of the 15 exhaust stroke and quickly close the slide valve at the end of the exhaust stroke.

The exhaust gases are taken from both 20 valve cases by a pipe 54, and it will be noted that this pipe is on the same side of the engine as and is disposed just below the discharge portion of the fresh gas pipe and that all these parts are on the opposite side of the engine from the inlet valve actuating means.

The operation of this engine is clearly 25 shown by the diagrammatic views 3 to 6 inclusive. When the piston 12 is beginning the power stroke as shown in Fig. 3, the exhaust and the inlet valve of a cylinder are held closed, and at the beginning of the 30 exhaust stroke, see Fig. 4, the exhaust valve is suddenly opened while the inlet valves are still held closed. At the beginning of the suction stroke, see Fig. 5, both inlet valves are opened simultaneously with the 35 closing of the exhaust valve. At the beginning of the compression stroke, see Fig. 6, both the inlet valves are closed, and so remain together with the exhaust valve until completion of the cycle. Any preferred 40 ignition mechanism may be employed, the present embodiment disclosing a spark plug 45 entering the compression space for this purpose, and preferably two sets of such

plugs are employed being disposed at opposite points in the compression space.

45

From the above description it will be seen that I have provided an internal combustion engine in which the fresh gas is let into the cylinder by spaced oppositely and simultaneously movable valves in the cylinder head 50 so that quick and uniform distribution of fresh gas throughout the cylinder above the piston is promoted.

What is claimed, is:—

1. In an internal combustion engine, a 55 water jacketed cylinder, a fresh gas space between the bottom of said water jacket and head of said cylinder, a pair of oppositely disposed valves located in said head and controlling the passage of gas from said 60 space into said cylinder, a lever pivoted between and serving to simultaneously open said valves, tension means for simultaneously closing said valves, and means for actuating said lever.

65

2. In an internal combustion engine, a cylinder having a transverse diaphragm in the head forming a fresh gas passage and a combustion chamber, a piston working in said combustion chamber, there being a pair 70 of ports in said diaphragm, a pair of valves seating in said ports, a bracket on the cylinder head between the stems of said valves, a rock lever fulcrumed on said bracket and operatively connected on opposite sides of 75 the fulcrum to said valve stems, and means for rocking said lever whereby to simultaneously move said valves in opposite directions to seal or unseal both of said ports.

In testimony whereof, I affix my signature, in the presence of two witnesses.

THOMAS L. FRATES.
